ELECTRON DISCHARGE TUBE

Frank D. Goodchild and Wilfrid E. Benham, Aldwych, London, England, assignors to Western Electric Company, Incorporated, New York, N. Y., a corporation of New York

Application May 4, 1933, Serial No. 669,320
In Great Britain May 6, 1932

4 Claims. (Cl. 250—27.5)

This invention relates to improvements in and relating to electron discharge tubes, and more particularly to an electrode structure for such tubes.

5 One object of this invention is to provide a complete electrode structure for an electron discharge tube, comprising, for example, a cathode, a control electrode or grid and an anode, which can be assembled as a single unit and subsequently mounted on the pinch of the tube, complete and ready for insertion in the bulb of the tube.

15 This method of construction is particularly advantageous in the case of tubes in which the inter-electrode distances are very small. In such tubes, a small variation in the electrode spacing will cause a considerable change in the characteristics of the tube. Hence, when such tubes have to be manufactured by the methods 20 of mass production, it is essential that uniformity be obtained between one tube and the next, or otherwise the characteristics of different tubes will show undesirable variations.

25 A further object of this invention is to provide a rigid assembly of the electrodes. This is also particularly important when the inter-electrode spacing is small since it is essential to ensure that there is no possibility of the electrodes touching, when the assembly is complete, either 30 due to vibration, for example, or in the process of mounting the electrode structure on the pinch of the tube. All these, and other desiderata are fulfilled by the arrangements of this invention.

35 In accordance with this invention we provide an electron discharge tube in which all the electrodes are assembled in a single rigid unit adapted to be mounted complete on the pinch of the tube.

40 Another feature of the invention is an electron discharge tube including an emissive cathode and two or more other electrodes provided with cooling fins and supported thereby, all the electrodes being supported and registered in position in a rigid unitary structure by insulating means.

45 A further feature of the invention is an electron discharge tube including at least an emissive cathode, and two or more other electrodes provided with cooling fins, all the electrodes being registered in position and supported between 50 two rigid insulating end members attached to the said cooling fins, to form a complete unitary electrode structure.

55 Other features of the invention will be apparent from the following description and the appended claims.

The invention is more particularly described with reference to the accompanying drawing in which:

Fig. 1 shows the component parts and method of assembly of a triode according to the present invention, and

Fig. 2 shows the completed structure.

The discharge tube in the embodiment of the invention shown is of the type described and claimed in our British Patent No. 360,433 in 10 which both the grid and anode are provided with cooling fins of considerable area in proportion to the area of the grid and anode structure. In the case, for example, of a three-electrode tube, the anode may be split to permit the passage 15 of the grid cooling fin, the grid and anode cooling fins being generally arranged in the same plane.

In the embodiment of the invention shown in the drawing, the grid electrode 1, which may be 20 of the type described and claimed in our British Patent No. 369,217, surrounds an indirectly heated cathode 2 and is provided with a cooling fin 3. The anode 4 in turn surrounds the grid and is split 25 to permit the passage of the grid cooling fin 3. The anode is provided with a cooling fin 6. Each cooling fin contains two grooves 7, 8 which embrace the electrode supporting rods 9, 10, respectively, these rods extending a short distance beyond the ends of the cooling fins. The indirectly 30 heated cathode 2, the grid 1 and the anode 4 are registered in position by insulating strips 11, for example, of mica, sufficiently thick to have considerable rigidity, each strip containing five small 35 apertures a, b, c, d, e, in a line. The insulating strips are arranged over the top and bottom of the electrode supporting rods 9, 10 whereby the indirectly heated cathode is supported between 40 the two central holes c, the grid electrode being supported between the two holes d, e, on one side 45 of the center and the anode between the two holes a, b, on the other side of the center. The strips 11 are held firmly in position by small collars 12, 13 which are slipped over the ends of the supporting rods extending through the strips and firmly clinched on to the supporting rods 9, 10. If desired a small washer may be inserted between the collar and the strip, and further the collars may be arranged on only one of the supporting 50 rods of each electrode, the other being free. A metal collar may also be provided where the indirectly heated cathode passes through the discs at c.

The ends of the cooling fins 3, 6, remote from the electrode portions 1, 4, are bent at right 55

angles at their edges, approximately level with the end of the strips 11, thereby forming two plane portions 14, 15 perpendicular to the cooling fins, which serve to give additional support to the insulating members.

It will be seen that we thereby provide a rigid electrode structure, in which all the electrodes are supported and registered firmly with respect to one another, and this single unit can be mounted as desired in a vacuum tube. In the preferred embodiment the electrode unit is mounted between two rigid supports 16, 17 (Fig. 2) held by the pinch of the tube and secured as by welding to the plane portions 14, 15 of the cooling fins which are at right angles to the main cooling fins 3, 6, as above referred to. One of the supports, 16, forms the conducting lead to the grid electrode and the other support, 17, the conducting lead to the anode. Connections are made by suitable flexible connections 18 to the heating element for the indirectly heated cathode and to the cathode itself. For preference the unit is mounted in an inclined position in the vacuum tube, as shown in Fig. 2 and the structure above described particularly facilitates this arrangement.

Although the invention has been described with reference to a three-electrode tube it is equally applicable to a 4-electrode, or to a pentode tube as described and claimed in our British Patent No. 360,433. It is equally applicable to the rectifier described and claimed in our British Patent No. 373,634.

The advantages of the construction according to this invention are many. As already pointed out the complete electrode structure can be assembled, with the electrodes properly spaced and arranged prior to mounting the arrangement on the pinch of the tube. The construction is simple and extremely rigid, which is very important in tubes of this type in which the clearance between the electrodes is normally very small. The large area of the cooling fins 3 and 6 and their lateral extensions 14, 15 provides efficient cooling so that the electrodes may be positioned very closely adjacent, for example, within a few millimeters of each other, whereby a high mutual conductance for the tube is obtained. If desired further cooling may be provided in higher power tubes by additional fins arranged laterally and perpendicular to the normal cooling fins and welded thereto.

What is claimed is:

1. An electron discharge device comprising an enclosing vessel, a unitary assembly therein including a pair of spaced insulating members having a plurality of apertures therein, a cathode

seated at opposite ends in corresponding apertures in said insulating members, a plurality of supports to one side of said cathode and having ends extending through corresponding apertures in said insulating members, means rigidly fixing said supports to said members, and an electrode having a portion in proximity to said cathode and having an outwardly extending portion secured to said supports, and means separate from said supports for mounting said unitary assembly within said vessel. 5

2. A unitary assembly for electron discharge devices, comprising a pair of spaced insulating members having aligned apertures, a cathode seated at opposite ends in corresponding apertures in said insulating members, a plurality of parallel rods having end portions extending loosely through corresponding apertures in said members, collars extending through said apertures for said rods, said collars surrounding and being secured to said end portions to fasten said rods to said members, and an electrode having a portion in proximity to said cathode and a fin portion secured to said rods. 10

3. An electron discharge device comprising an enclosing vessel having a stem, a plurality of supporting members extending from said stem, an anode having a cylindrical portion and a fin secured to one of said supporting members, a grid electrode having a cylindrical portion within the cylindrical portion of the anode, and a fin secured to another of said supporting members, a cathode within said cylindrical grid portion, a plurality of rods separate and spaced from said supporting members, mounted on and extending beyond the ends of each of said fins, and insulating spacer members disposed one adjacent each end of said fins, said spacer members having apertures through which said rods pass and having apertures for receiving said cathode. 25 30 35 40

4. An electron discharge device comprising an electrode having a cylindrical portion and a flanged fin, a second electrode having a helical portion within said cylindrical portion and a flanged fin substantially coplanar with said first flanged fin, rod members mounted on and extending beyond the ends of said fins, a cathode within said helical portion, a pair of insulating members disposed at opposite ends of said fins and seated thereon, said insulating members having apertures through which said rods pass, and fastening means engaging said insulating members and said rods for securing said insulating members against said fins. 45 50 55
